Des. 215,244
Patented Sept. 16, 1969

215,244

ELECTRIC PIANO

Harold B. Rhodes, Anaheim, Calif., assignor to Columbia Broadcasting Systems, Inc., New York, N.Y., a corporation of New York

Filed Aug. 15, 1968, Ser. No. 13,143

Term of patent 14 years

Int. Cl. D17—01

U.S. Cl. D56—9

FIG. 1.

FIG. 2.

FIG. 3.

FIG. 4.

FIG. 5.

FIG. 6.

FIG. 7.

FIG. 14.

FIG. 8.

FIG. 9.

FIG. 10.

FIG. 11.

FIG. 12.

FIG. 13.

FIG. 1 is a perspective view of an electric piano, showing a first form of my new design;

FIG. 2 is a top plan view of the form shown in FIG. 1;

FIG. 3 is a front elevational view of the form shown in FIG. 1;

FIG. 4 is a side elevational view of the form shown in FIG. 1;

FIG. 5 is a rear elevational view of the form shown in FIG. 1;

FIG. 6 is a bottom plan view of the form shown in FIG. 1;

FIG. 7 is a top plan view, partly in cross-section, taken on line 7—7 in FIG. 3;

FIG. 8 is a perspective view of an electric piano, showing a second form of my new design;

FIG. 9 is a top plan view of the form shown in FIG. 8;

FIG. 10 is a front elevational view of the form shown in FIG. 8;

FIG. 11 is a side elevational view of the form shown in FIG. 8;

FIG. 12 is a rear elevational view of the form shown in FIG. 8;

FIG. 13 is a bottom plan view of the form shown in FIG. 8; and

FIG. 14 is a top plan view, partly in cross-section, taken on line 14—14 in FIG. 10.

The sides not shown in FIGURES 4 and 11 are mirror images of the sides shown therein.

The dominant features of my new design reside in the portions shown in solid lines.

I claim:

The ornamental design for an electric piano, substantially as shown and described.
